UNITED STATES PATENT OFFICE.

LOUIS A. MILLER, OF NEW HAVEN, CONNECTICUT, ASSIGNOR TO WINCHESTER REPEATING ARMS COMPANY, OF NEW HAVEN, CONNECTICUT, A CORPORATION OF CONNECTICUT.

FLASH LIGHT.

1,421,528.

Specification of Letters Patent.

Patented July 4, 1922.

Application filed July 14, 1921. Serial No. 484,589.

To all whom it may concern:

Be it known that I, LOUIS A. MILLER, a citizen of the United States, residing at New Haven, in the county of New Haven, State 5 of Connecticut, have invented certain new and useful Improvements in Flash Lights; and I do hereby declare the following to be a full, clear, and exact description of the invention, such as will enable others skilled 10 in the art to which it appertains to make and use the same.

My invention is an improvement in flashlights, and relates especially to a new and improved form of latch mechanism for retaining the lid or cover in closed position.

In the usual construction of flashlights the case is open at one end, to permit the removal and insertion of the battery. A lid or cover is provided for closing the end of 20 the case, the lid or cover being hinged to the case at one side, and having latch mechanism at the other for holding it closed.

This latch mechanism is usually in the form of an integral tongue on the cover, engaging a catch or shoulder on the case, the tongue being held in engagement with the catch by its own resiliency, and both tongue and shoulder, in order that the battery space be not encroached upon, are outside the case.

30 The extremity of the tongue is curved outwardly away from the case to facilitate its release, when desired, and presents a projection prone to catch in the clothing or on other obstructions. The tongue is of relatively light sheet material and when so caught the cover may be jerked open, with consequent displacement of the parts. Furthermore, the tongue is liable to be bent in such manner that it will not closely engage 35 the shoulder and a repetition of such bending will finally make the latch inoperative, and may cause the tongue to break away from the cover.

The object of the present invention is to 45 provide a construction of latch mechanism such that while the battery space is not encroached upon, the latch mechanism is within the case, and presents no projections to catch upon obstructions.

50 In the drawings:

Fig. 1 is a side view of a flash light of usual construction provided with the improved latch mechanism, and with a part in section.

55 Fig. 2 is a plan view of the same.

Fig. 3 is an end view looking at the cover. Fig. 4 is an enlarged section through the latch mechanism.

The present embodiment of the invention is shown in connection with a flashlight of 60 usual construction, comprising the case 1, having at one end a socket for supporting the bulb 2 and having at the other a lid or cover 3, which is hinged to the body of the case at one side of the cover, as indicated at 4. 65

The latch mechanism comprises a tongue 5 integral with the cover in the present instance and this tongue has a transverse groove 6, adapted to engage a similarly shaped shoulder 7 on the case. The shoulder is, however, in the present instance inside of the case being formed within a species of sheath 8. The sheath is provided for by outwardly offsetting a portion of the side wall of the case, far enough so that the 75 tongue 5 will slip into the same but not so far that an unsightly projection will be presented. The transverse groove 6 is formed on the outer face of the tongue and the rib 7 is on the inner face of the sheath wall. 80 With this arrangement there is no possibility of the tongue being engaged with foreign objects, to bend the same, or to open the cover, and the case presents a neater and more finished appearance at this point. The 85 cover is easily opened by engaging the same with the thumb nail adjacent to the sheath. It will be obvious that if desired the cover might be extended slightly on each side of the sheath to form a point of engagement for 90 the nail.

I claim:

1. In a flashlight, the combination with the case, and the cover hinged at one side to the case and latch mechanism for holding 95 the cover to the case, and comprising a tongue on the cover and a catch on the case wall, that portion of the wall carrying the catch being offset outwardly beyond the plane of the wall thereby to leave the interior of the case unobstructed by the latch mechanism.

2. In a flashlight, the combination with the case, and the hinged cover, of latch mechanism in connection with the cover and case 105 for holding the cover closed, said mechanism comprising a resilient tongue upon the cover, and a sheath in connection with the case wall in which the tongue engages, the case wall being offset outwardly to form said 110

sheath, thereby to leave the interior of the case unobstructed.

3. In a flashlight, the combination with the case, and the hinged cover at the end thereof, of latch mechanism in connection with the cover and case for holding the cover closed and within the case when the cover is closed, said mechanism comprising a re-

silient tongue upon the cover, and an outwardly offset portion on the casing wall into which the tongue extends, the tongue and outwardly offset portion having interengaging means for holding the cover closed.

In testimony whereof I affix my signature.

LOUIS A. MILLER.
